UNITED STATES PATENT OFFICE.

JOHN H. KING, OF PHILADELPHIA, PENNSYLVANIA.

DANCING TOY.

1,322,456.

Specification of Letters Patent.

Patented Nov. 18, 1919.

Application filed February 4, 1919. Serial No. 274,904.

To all whom it may concern:

Be it known that I, JOHN HENRY KING, a citizen of the United States, residing at 1108 Mount Vernon St., Philadelphia, in the 5 county of Philadelphia and State of Pennsylvania, have invented new and useful Improvements in Dancing Toys, of which the following is a specification.

The invention relates to games and toys, 10 and more particularly to toys, and has for an object to provide a toy that may be employed for purposes of amusement, as well as for advertising or other purposes, and in which a simple apparatus and mechanism is 15 used to bring about the effect of figures dancing upon a floor or platform.

The invention comprehends among other features, a toy which might be more particularly termed a dancing toy, and in which the 20 figures are arranged to dance around a circular floor or platform, and in which each set of figures independent of the other, rotates around the circular floor or platform, and also turn about themselves eccentrically 25 to the rotating axis, bringing about a genuine dancing effect in which certain sets of the figures will come closer to each other and then move farther apart during the dancing operation.

30 Still further the invention comprehends a dancing toy, in which the mechanism employed to bring about the desired result is of a simple construction, can be easily operated, and will not readily get out of order.

35 In the further disclosure of the invention, reference is to be had to the accompanying drawings, constituting a part of this specification, in which similar characters of reference denote corresponding parts in all the 40 views, and in which,—

Figure 1—is a vertical sectional view taken through the device showing a casing, the dancing figures and the relative position of the actuated apparatus.

45 Fig. 2—is a plan view of the platform and rotating element, the casing and figures having been removed, and with a portion of the operating or driving mechanism shown partially in sections.

50 Fig. 3—is a fragmentary plan view of a slightly modified form of device, and

Fig. 4—is a side elevation of the structure shown in Fig. 3.

Referring more particularly to the views, 55 I provide a substantially rectangular casing 10, which may be made of wood, card-board

or any other suitable material, a driving or operating apparatus or mechanism 11, being secured in one corner of the casing 10 and consisting substantially of a suitable crank 12 journaled in a block 13 and carrying on its inner end a beveled toothed wheel 14 in mesh, with a second beveled toothed wheel 15 carried on a vertical shaft 16 to which is keyed a pulley 17. From the pulley 17 extends a belt 18 which may be of an elastic nature, and which passes around a main supporting or driving wheel 19 journaled upon a vertically disposed stud 20 secured in a base block 21, in the casing 10. It will now 60 be apparent that the rotation of the crank 12, will, through the medium of the belt 18 bring about the rotation of the driving element 19. A series of vertical studs 22 are secured in the driving element 19, and journaled on each stud is a suitable circular platform 23, having a suitable floor covering 24 with a periphery of each platform encircled by a friction band 25. Suitably keyed or otherwise secured to the main upright or 65 stud 20 is a supplementary driving wheel 26, and having the periphery thereof, encircled by a friction band 27, thus providing the friction driving wheel with the encircling band 27 in frictional contact with the friction bands 25 of the circular platforms 23. On each floor covering 24 of each platform 23, a plurality of figures 28 are suitably 70 secured, and by reference to Fig. 2, it will be seen that these figures are not mounted 75 upon the central part of the floor covering or centrally of the axis of the platform, but nearer the edge thereof, so that the figures will be disposed eccentrically of the axis of each platform. A covering 29 is provided 80 for the top of the casing with openings 30 cut therein, through which the floor coverings 24 and platform appear, and the covering 29 may be made of any suitable material and polished or decorated to represent 85 a floor, or finished off in a wood effect.

Referring now to Figs. 1, 2, it will be seen that when the supporting and driving wheel or element 19 is rotated by the action of the belt 18, the circular platforms 23 will 90 rotate with the driving element 19, and due to the fact that their friction bands are in frictional contact with the friction band 27 of the stationary centrally disposed friction element 26, each platform will be individually rotated about its own axis, aside from rotating around the central axis of the sup- 95 100 105 110

porting and driving element 19. This will give to the figures the effect of dancing and by having the figures mounted near the peripheries of the individual platforms, and 5 near the edges of the floor coverings thereof, the rotation of the individual platforms will cause the different sets of figures to move toward and away from each other in the 10 operation of the device thus bringing about a more realistic dancing effect, which would not appear if the figures were centrally mounted upon the individual platforms.

In Figs. 3, 4, I show a slightly modified form of my device, and in which instance 15 each individual platform designated by the numeral 23^a, is journaled upon an off-set support or shaft 23^b, with a suitable roller 23^c also journaled on each angular support or off-set shaft fixed to the underside of the 20 platform, a spring being provided in each instance, and designated by the numeral 23^d, one end of said spring being secured to the support 23^b, and the other end to the main supporting and driving wheel or element 25 indicated by the numeral 19^a, and which is substantially the same as the supporting and driving element shown in the preferred form of my invention.

From the foregoing description it will be 30 seen that with the device set forth, a realistic dancing effect is secured and as mentioned heretofore, I find that the same is successfully obtained by having the figures set to one side or eccentrically of the supporting 35 uprights or shafts of the platforms on which the figures are mounted. I am aware that various forms of dancing toys have been employed heretofore, but in a number of these cases I find that the figures are disposed 40 centrally, with respect to the axis of the rotating element and thus they simply turn around, rotating on the axis, and are always substantially spaced an equal distance apart.

In my device however, by having the figures 45 close to the edge of the individual platforms upon which they are mounted, the figures

move toward and away from each other, that is one set of figures will approach very close to, and almost contact with the adjacent set of figures at a certain time, and immediately 50 thereafter will tend to move away from the second set of figures, and it is by this action that I secure a realistic dancing effect. For the purpose of supplying music to accompany the dancing figures I provide a series 55 of bells 31, depending from the underside of the covering 29, and which bells although they will tingle in the ordinary rotation of the device, tend to come in contact with the belt, 18, and upon striking the belt, in the rotation of the device, the bells will be jingled to provide the necessary musical effect. It will of course be understood that any other form 60 of musical effect can also be used in connection with the device described, and from the foregoing it will be seen that the apparatus is of a simple construction, can be easily 65 operated, and due to the simplicity of its parts cannot readily get out of order.

Having described my invention, I claim,— 70

A toy comprising in combination with a rotatable supporting and driving element, a plurality of platforms mounted to turn loosely upon said element and rotatable therewith about its axis, a centrally disposed 75 friction element, means insuring frictional engagement between the platforms and the friction element to insure individual rotation of the platforms, when said friction element is rotated with the driving element, 80 and about its axis, and figures mounted upon said platforms to rotate therewith, said figures on each platform being disposed eccentrically to the axis of each platform and adjacent the periphery thereof, to insure a 85 constant varying of the distance between the figures on one platform and the figures on the adjacent platform when the toy is operated.

In testimony whereof I affix my signature. 90

JOHN H. KING.
